ABSTRACT: A clothes-hanging rack for motor vehicles is provided which hugs the car ceiling, and is neat, inexpensive, inconspicuous and completely out of the way when not in use. The hanger includes a tough hollow frame or housing and a series of distinct hanger-supporting fingers, normally contained, and individually retained, within the housing. Each finger is bendable under the weight of a garment hanger, and the garment carried thereby, and each has its own assigned position so that the hangers do not slide from side to side as the car rounds curves. The frame stands as an upholstery guard between the finger-supported hangers and the ceiling upholstery, as well as a housing and support for the fingers.

GARMENT-HANGING RACK FOR MOTOR VEHICLES

This invention relates to a clothes-hanging rack for motor vehicles, having for its primary object the provision of a thin rack which hugs the car ceiling so that it is completely out of the way and inconspicuous when not in use, but has the capability of supporting many hangers together with the garments carried by the hangers.

It is an important feature that the rack includes a hollow frame or housing and multiplicity of flexible individual hanger-supporting fingers, each finger being fixed at one end and having a definitely assigned position, and each having a free end portion normally confined in the housing but individually bendable to an active position in which it may carry a garment hanger and whatever load is applied to the hanger.

It is a further feature that the frame is disposed to provide not only a support and housing for the fingers, but a protective shield for preventing contact of the fingers and the finger-supported hangers with the ceiling upholstery of the car.

It is still another feature that the fingers, through individually bendable and free of rubbing contact with one another, form integral parts of a single finger-forming strip.

It is another feature that the frame has opposed, spaced-apart, inturned lips at its lower boundary, one fixedly supporting the continuous portion of the finger strip, and the other normally supporting the tip portion of each finger individually, the arrangement being such that any finger can be sprung down past the finger-supporting lip into active position by displacing neighboring fingers upward to afford access to the desired finger and then pulling the desired finger downward.

Other objects and advantages will hereinafter appear.

In the drawing forming part of this specification,

FIG. 1 is a view showing an illustrative hanger rack, which constitutes a practical and advantageous embodiment of the invention, connected by fasteners which pass through the ceiling upholstery, to a transverse frame member of the car ceiling, the view being a sectional view taken on the line 1-1 of FIG. 2, but being on too small a scale to make hatching of the upholstery feasible;

FIG. 2 is a transverse vertical sectional view on a considerably larger scale than FIG. 1, the section being taken on the line 2-2 of FIG. 1, looking in the direction of the arrows;

FIG. 3 is a fragmentary inverted plan view of the hanger rack of FIGS. 1 and 2, on the scale of FIG. 2;

FIG. 4 is a view similar to FIG. 3 of a structure in which a modified configuration of the fingers is shown; and

FIG. 5 is a view similar to FIG. 2, showing a further modified form of rack.

In FIG. 1 the roof or ceiling 10 of the car comprises a conventional outer metallic shell 12, and a frame which includes metallic crossmembers, one of which, designated 14, is shown as the foundation member to which my novel hanger rack 16 is attached by screws 18. The screws 18 are passed upward through ceiling upholstery 20 and are threaded into the metallic crossmember 14. Since the use of the rack both as factory equipment on new vehicles and as accessory equipment on existing vehicles is contemplated, the screws 18 are desirably of the self-tapping variety; i.e., case hardened so that they will cut their own threads in metal when predrilled holes of appropriate size are provided. In FIG. 1 irrelevant details concerning the exact contour of the car exterior have been ignored.

The hanger rack 16 comprises a hollow rigid frame or housing 22 which conforms to the contour of the inner face of the frame member 14 throughout that portion of the member 14 which extends straight or nearly so, the length of the frame desirably measuring somewhat less than the width of the car interior, but, as shown, considerably more than half of the width. Alternatively, two aligned, spaced racks may be provided, each of a length less than half the width of the car interior. The top, front and rear walls of the frame are continuous, but the lower wall of the frame is incomplete, consisting

of a rearwardly extending forward lip 24 and a forwardly extending rear lip 26. The frame may be provided with infolded end portions 28 or may be closed off in any other way at its ends which will present an attractive appearance.

Within the bounds of the frame there is provided a hanger strip 30 of strong, tough, resilient, bendable material, either of a suitable metal or of a suitable plastic. The strip 30 is continuous along its rear margin and provision is made for firmly and fixedly securing this rear, continuous portion in place, upon the inner surface of the rear lip 26. As shown, the rear portion is formed with an upstanding continuous flange 32 which bears against the rear wall of the frame and may be held firmly in place by a continuous filler block 34. The parts are also held together by short screws 35.

The forward portion of the strip 30 is divided in individual forwardly reaching, resilient hanger rack fingers 36 which stand side by side, but are spaced far enough from one another so that no substantial rubbing or conflict will ever occur.

Each finger 36 is recessed to receive the hook of a garment carrier, being desirably formed with a slot 38 as shown in FIG. 3, with the slot of progressively increasing width from rear to front, and broad enough at its forward end to receive the hook portion of an individual garment hanger hook.

In the normal position, in which all the fingers are shown in FIG. 3, the tip of each finger stands just above the lip 24, being confined by the lip. The fingers do not naturally assume this position, but under slight upward pressure each will bend, pass upward beyond the lip and then spring out to a straight condition. This is a very neat arrangement since every portion of the strip lies within the bounds of the frame and the lower faces of the fingers are caused to stand in a common plane. Each finger can bend under the weight of the hanger carried by it and the load carried by the hanger as the car accelerates, turns, encounters uneven road conditions, or is braked, but each finger has its own definitely assigned position so that the hangers cannot slide first to one side of the car and then to the other.

For maintaining a clear view through the rear view mirror two short aligned racks may be provided, one at each side of the car. If a long rack is provided, as shown, a selected central group of fingers may be held out of service unless and until they cannot be spared.

In FIG. 4 the structure is the same as that shown in FIG. 3 with one exception. Each finger 36a is recessed to receive the hook of a garment hanger, being formed in this instance to provide hooks rather than slots, the fingers being essentially C shaped. This provides more hanger hook insertion space, and facilitates access to a finger for pulling it down past the lip 24 when it is wanted for use. Corresponding reference numerals have been applied to corresponding parts in FIG. 4 with the postscript added in each instance.

The structure of FIG. 5 may be like that of FIGS. 1 to 3, with fingers of the shape shown in either FIG. 3 or FIG. 4. The rack 16b is a single integral structure composed of strong, tough, flexible plastic, however. The fingers 36b are considerably thinner and more flexible than the lip 26b, but they are integral with it. Because of the difference of thickness of the frame and the fingers, the frame may be tough and substantially rigid with the fingers comparatively freely bendable. Corresponding reference characters have been applied to corresponding parts in FIG. 5 with the postscript *b* added in each instance.

I have described what I believe to be the best embodiments of my invention.

I claim:

1. A garment-hanging rack for motor vehicles comprising, in combination,
  - a thin, tough, hollow frame or housing adapted to be attached at the underside of the ceiling upholstery to a transverse, rigid member of the car ceiling, and to conform to the interior contour of the ceiling throughout a substantial portion of the width thereof, said frame having vertically disposed front walls and backwalls and a partial lower wall consisting of a rear lip that extends forward

from the backwall and a forward lip that extends rearward from the front wall, the lips being substantially spaced from one another; and

b. a multiplicity of bendable spring fingers, each fixedly connected at one end to one of the lips, but having an opposite free end, each spanning the space between lips and normally contained within the bounds of the housing frame, and each recessed to receive the hook portion of a conventional garment hanger;

the construction and arrangement being such that each finger has a definitely assigned position lengthwise of the rack, and that the free end of each finger, in fully extended condition, is disposed to overlap slightly the adjacent lip of the housing, but may, by a slight bending, be pushed up past the edge of the lip to its normal, idle position, or drawn down past the lip to an active position.

2. A garment-hanging rack for motor vehicles as set forth in claim 1 in which the front and rear walls of the housing extend uninterruptedly from end to end of the active portion of the hanger rack and positively prevent engagement of the finger-supported hanger hooks with the ceiling upholstery of the vehicle.

3. A garment hanging rack for motor vehicles as set forth in claim 1 in which the several spring fingers form integral parts of a single, resilient strip, the strip being continuous along one

10
15

margin and having that margin firmly and fixedly attached to the frame lip by which it is supported.

4. A garment-hanging rack for motor vehicles as set forth in claim 3 in which each finger is spaced from its neighbors by a small amount, adequate to prevent conflict and rubbing of the fingers.

5. A garment-hanging rack as set forth in claim 4 in which the hook-receiving recess of each finger is formed as a slot capable of receiving the hook of a garment hanger through it.

6. A garment-hanging rack as set forth in claim 5 in which each finger slot increases in width from the slot end nearer the frame-connected end of the finger to the opposite slot end, whereby the finger is caused to be progressively more freely bendable toward its free end.

7. A garment-hanging rack as set forth in claim 4 in which the hook-receiving recess of each finger is formed as a side notch in the finger, the finger being essentially C shaped.

8. A garment-hanging rack as set forth in claim 1 in which the fingers are integral with the rack frame, the frame, however, having walls that are comparatively thick, and therefore comparatively rigid, and the fingers being much thinner than the rack walls so that the fingers are comparatively freely bendable.
